UNITED STATES PATENT OFFICE

155,014

DESIGN FOR A COMBINED KNIFE RACK AND CONDIMENT SHAKER HOLDER

Philip H. Kitzler, Chicago, Ill.

Application April 23, 1947, Serial No. 138,553

Term of patent 7 years

(Cl. D44—29)

To all whom it may concern:

Be it known that I, Philip H. Kitzler, a citizen of the United States, residing at Chicago, in the County of Cook and State of Illinois, have invented a new, original, and ornamental Design for a Combined Knife Rack and Condiment Shaker Holder, of which the following is a specification, reference being made to the accompanying drawing, forming a part thereof.

In the drawing:

Fig. 1 is a front elevational view of a combined knife rack and condiment shaker holder embodying my new design;

Fig. 2 is a side elevational view thereof;

Fig. 3 is a top plan view of the same; and

Fig. 4 is a vertical sectional view on line 4—4 in Fig. 1.

I claim:

The ornamental design for a combined knife rack and condiment shaker holder, substantially as shown.

P. H. KITZLER.
